UNITED STATES PATENT OFFICE.

MICHAEL IVERSEN, OF STOUGHTON, WISCONSIN.

SURGICAL APPLIANCE.

1,111,588.

Specification of Letters Patent. Patented Sept. 22, 1914.

Original application filed August 2, 1912, Serial No. 712,836. Divided and this application filed January 8, 1914. Serial No. 811,017.

To all whom it may concern:

Be it known that I, MICHAEL IVERSEN, a citizen of the United States, and a resident of Stoughton, in the county of Dane and State of Wisconsin, have invented a new and Improved Surgical Appliance, of which the following is a full, clear, and exact description.

This invention relates generally to surgical appliances, as described in my application, Serial No. 712,836, filed August 2, 1912, of which this application is a division and more particularly, it is directed to a new and improved combination of fountain, dropper, and tube which is especially adapted for use in douching.

The principal object of my invention is to provide a surgical appliance characterized by a construction of parts adapting it to the purposes of a douche generally and also adapted to permit the flow of a given amount of the fluid in a given time, thereby providing a proctoclysis apparatus.

The invention comprehends a combination of improved parts which are a fountain can, a dropper, and an improved form of tube, the apparatus being characterized by the fact that gases may be returned therethrough without affecting the operation thereof.

A further object of the invention is the provision of a reversible dropper through which the fluid is adapted to be passed either in large quantities, as in giving enemas, or in certain determined quantities, as in proctoclysis, a path for return gases being provided in the article.

A still further object of the invention is the provision of a new and improved fountain can which is particularly adapted for use with the dropper described.

Reference is to be had to the accompanying drawings, forming part of this specification, in which similar characters of reference denote corresponding parts in all the views, and in which—

Figure 1 is a side view, partly sectional, of the appliance; Fig. 2 is a vertical sectional view of the dropper, while Fig. 3 is a sectional view of the tube and the nozzle carried thereby.

It will, of course, be understood in the description of the construction and the operation of the invention that the questions of

size of the different parts and the material of which they are made are largely matters of choice and skill and different physical embodiments of the inventive idea may be provided, differing widely in appearance and form without departing from such inventive idea.

The appliance comprises a fountain can or irrigator 1 of any desirable material, preferably enameled ironware, and provided with a scale on the inside in order that the quantity of fluid contained therein may be easily determined, the can being preferably provided with a cover 2 and some means whereby it may be suspended in position, as a perforated projection 3. The cover 2 is removed when the device is in use and may be omitted, as it serves only to protect the contents of the can. Adjacent the lower end of the can is a valve or stop cock 4 and extending from the top portion of the can is a handle 5 made up of a hollow tube having the opening 6 extending therethrough, the opening communicating with the interior of the can 1, and with the outside of the said valve or stop cock 4; the opening 6 in the handle 5 may be brought into communication with the outlet in the lower portion of the can through the stop cock 4 in any desirable manner, the idea being that from the junction 7 two paths are provided to the interior of the can.

Beyond the point 7 and communicating with the two passages to the interior of the can is a tube 8 of any desirable form or material and of any desired length, one end of a dropper 9 of transparent material, being secured to the other end of this tube, while beyond the dropper is a further tube 10 of particular construction having a metal nozzle 11 provided with a shoulder 12 and a number of openings 13.

Referring particularly to Fig. 2, it will be noted that the dropper 9 is preferably of integral construction and is provided with the inner partition 9^a, whereby a plurality of chambers 17, 18, are provided, the chambers communicating with the said tubes 8 and 10 by means of the constricted and open end portions 16. The partition 9^a is of peculiar construction and is provided on opposite sides thereof with the nozzles 14, whereby the chambers 17, 18, are in communication with each other through a plurality of

passages which extend through these nozzles, it being noted that the outer ends 15 are curved as shown. The construction of the dropper is symmetrical so that it is therefore 5 reversible and either end may be made the top or bottom thereof. The outer end of the tube 10 which terminates in a nozzle 11 is of particular construction and is shown particularly in Fig. 3. It is preferably of the 10 conformation shown, and comprises a metal tube 10^a with a rubber or similar covering 10^b, the metal tube being preferably provided with the integral shoulder 12 and the metal nozzle 11 with the openings 13 therein, the shoulder being provided in order that the nozzle may be retained in the opening in which it is placed to a determined depth.

The use of the apparatus is as follows:— The fluid to be used is placed in the fountain 20 can after removing the cover 2 and if only a given number of drops per minute are to be administered, the stop cock 4 may be regulated and the number of drops may be counted by viewing the interior of the dropper. 25 The nozzle 11 or metal tip is inserted and, if this tip has been previously warmed, it may be left in position for some time, since it will quickly come to the temperature of the body. If the apparatus is to be used in giving 30 enemas, of course, the dropper is not of such importance but may, however, be left in position, the fluid passing therethrough. The particular value of the dropper, as well as the peculiar construction of the fountain 35 can, lies in the fact that gases which are returned may pass through the tube and the dropper and enter the can through the passageway or opening 6 in the tubular handle without affecting the flow of the fluid 40 through these parts, due to the plurality of passageways between the compartments of the dropper and the hollow handle. The appliance may be left in position with respect to the body between treatments, if so desired, 45 and when so used provides for the return of gases, thereby relieving abdominal pains.

The appliance shown and described does away with all contrivances for keeping any solution hot in order to dispense it at the 50 temperature of the body, especially in the case of proctoclysis when only 40 to 60 drops per minute are allowable, since the metal tip or nozzle and the metal tube with the insulating or rubber covering will come to the 55 temperature of the body. It will also be seen that there will be no effect or back pressure on the dropper, as the pressure will be the same on both sides of the partition 9^a and owing to the fact that the fluid will flow 60 through one of the nozzles 14, namely the one which is directed downwardly, the free return of gases and the liquid through the other nozzle, which is directed upwardly, will be permitted in the event of an 65 explosive effort on the part of the pa-

tient. Another advantage of the device over such devices employing the siphon principle, is that there is no need for a plurality of receptacles, nor clips for attaching the tubes to the receptacles and furthermore, 70 the device possesses distinct advantages due to its operation by static pressure, instead of by a siphon action. The employment of these different hydrostatic laws is such that in the present device when the flow is caused 75 by the hydrostatic head of water or fluid in the receptacle, there is a more steady flow and there is no tendency to aerate the fluid in such a manner as would occur in a device employing a siphon action, which due to the use of two columns of equal height counter-balancing each other, produces a head effective only as the depth of the fluid varies 80 and the tendency to aerate the fluid is graduated by the natural tendency 85 for the air to escape with the fluid, which would naturally result in back pressure and this is obviated by applicant's device. Furthermore, it is not necessary to fill the discharge tube before starting 90 the apparatus or creating suction at the discharge end and as this is not always permissible, but is necessary in the case of the siphon apparatus, some advantage is derived 95 in this regard.

Having thus described my invention, I claim as new and desire to secure by Letters Patent:—

1. The combination of a receptacle, a valve adjacent the bottom thereof, a tube 100 communicating with the valve and depending therefrom, a tube communicating with the aforesaid tube outwardly of the valve and having a curved upper end communicating with the receptacle adjacent the top of the latter, a dropper connected to the depending tube, and a discharge tube having a nozzle, said discharge tube being connected to the dropper, whereby during the flow of the fluid from the can through the nozzle, 110 a return for gases will be effected through the dropper and second-mentioned tube.

2. A fountain can, comprising a receptacle, a rigid passageway extending horizontally therefrom near its bottom, a single valve in said passageway, another rigid passageway, said second passageway extending outward from the receptacle adjacent to the top thereof and extending downwardly to communicate at its lower end with the first 115 passageway outwardly of the valve, a flexible discharge tube carried thereby, and a nozzle at the free end of the tube.

3. A fountain can, comprising a receptacle, a valve adjacent the bottom thereof and providing a passageway therefrom, another passageway adjacent to the top of the receptacle and extending substantially vertical and curved at its upper end to communicate with the interior of the receptacle, said sec- 125

ond passageway communicating with the first passageway outwardly of the valve, a flexible discharge tube carried thereby, a nozzle at the free end of the tube, and dropping means between the passageways and the discharge tube to render visible the flow of the fluid and to permit the return of the fluid or gas under pressure.

In witness whereof I have signed my name to this specification in the presence of two subscribing witnesses.

MICHAEL IVERSEN.
